UNITED STATES PATENT OFFICE

EDWARD J. SCHAUB, OF WHEELING, WEST VIRGINIA, ASSIGNOR TO CENTRAL GLASS WORKS, OF WHEELING, WEST VIRGINIA, A CORPORATION OF WEST VIRGINIA

DESIGN FOR A GLASS GOBLET OR SIMILAR ARTICLE

Application filed January 2, 1930. Serial No. 33,997. Term of patent 7 years.

To all whom it may concern:

Be it known that I, EDWARD J. SCHAUB, a citizen of the United States of America, and resident of Wheeling, county of Ohio, and State of West Virginia, have invented a new, original, and ornamental Design for a Glass Goblet or Similar Article, of which the following is a specification, reference being had to the accompanying drawings, in which—

Figure 1 is a side elevation of a glass goblet or similar article, showing my new design;

I claim:

The ornamental design for a glass goblet or similar article, substantially as shown.

EDWARD J. SCHAUB.
